Primary Examiner — Derrick Holland*Assistant Examiner* — Yolanda Robinson(74) *Attorney, Agent, or Firm* — Taylor IP, P.C.(57) **CLAIM**

The ornamental design for a flex fork wheel support assembly, as shown and described.

DESCRIPTION

FIG. 1 is a bottom perspective view of a flex fork wheel support assembly showing my new design;

FIG. 2 is a bottom view thereof;

FIG. 3 is a top view thereof;

FIG. 4 is a side view thereof;

FIG. 5 is an opposite side view thereof;

FIG. 6 is a front view thereof;

FIG. 7 is a rear view thereof; and,

FIG. 8 is a top perspective view thereof, shown in environmental use.

The broken lines shown represent unclaimed subject matter and form no part of the claimed design.

1 Claim, 6 Drawing Sheets(56)
